UNITED STATES PATENT OFFICE

OLAF LARSEN, OF FORT ATKINSON, WISCONSIN, ASSIGNOR TO THE CREAMERY PACKAGE MFG. COMPANY, OF CHICAGO, ILLINOIS, A CORPORATION OF ILLINOIS

MECHANISM FOR CAPPING BOTTLES

Application filed September 14, 1928. Serial No. 305,957.

The invention relates to mechanical devices for placing closure caps upon milk bottles, and more particularly relates to the means therein for transferring a cap from a stacked supply to the bottle upon which it is to be placed.

The handling by such devices of milk bottle caps, other than the plain flat discs in more common use, often involves difficulty in transferring a cap from the supply stack to the bottle by reason of the cap falling out of proper position for the succeeding operation of impressing the cap within the mouth of the bottle.

It is the principal object of the invention to provide in a milk bottle capping device means for retaining control of the position of the cap during its transfer to the bottle so that it is in proper register with the mouth of the bottle for seating therein with complete closure of the bottle.

Other objects and advantages will be apparent in the following description of a preferred embodiment of the invention which I have illustrated in the accompanying drawings. It will be understood, however, that various changes in form construction and arrangement may be made by those skilled in the art without departing from the scope and spirit of the invention as expressed in the appended claims.

In the drawings, Fig. 1 represents a side view in elevation of a hand operable capping device in which the invention has been incorporated. Fig. 2 is a front view in elevation having a portion of the device shown in section as taken on the plane of the line 2 in Fig. 1.

Referring to the drawings, the numeral 1 indicates a tubular body having a bell shaped end portion 2 adapted to receive the mouth end of a bottle to be capped, the cap and a plunger for seating it in the bottle passing down through the inner chamber 3. Extending laterally from the body 2 is a bracket 4 having a slideway 5 upon which is operatively supported a sliding block 6. An upper tubular body 7 is secured to and concentric with the lower body 1, as by means of screws 8, the body 7 having a lateral extension 9 posi-

tioned over the bracket 4 and serving to retain the block 6 in the slideway 5.

Formed upwardly on the extension 9 is a ring 10 adapted to receive and support a tubular container of bottle caps (not shown), the container being further supported by another ring 11 formed laterally upon the upper end of the body 7. An opening 12, from within the ring 10 through the extension 9, permits the bottle caps stacked in their usual tubular container to pass by gravity successively into the path of a cap slide 13 carried by the block 6, the bottom cap of the stack being retained in such position by means of a pair of spaced guides 14 between which the slide 13 operates.

With the block 6 in rearward position, the slide 13 is retracted rearward of the opening 12 and a cap drops into position before the slide. Forward movement of the block 6 and slide 13 pushes the cap forward through a slot 15 opening into the chamber 3, through which latter the cap descends to the mouth of the bottle as hereinafter described.

The reciprocatory movement of the block 6 is accomplished by means of a pair of levers 16, pivotally supported at their upper ends upon lugs 17 formed upon opposite sides of the upper end of the body 7. The lower ends of the levers 16 are operatively connected to opposite ends of the block 6 by a pair of links 18. The levers 16 are actuated by a pair of rollers 19 mounted on a cross pin 20, the rollers respectively being engaged within a cam slot 21 formed in each of the levers 16, the cam slots being arranged to cause the levers to swing upon vertical movement of the cross pin 20.

The cross pin 20 extends through opposite longitudinal slots 22 formed in the body 7, and is fixed in a longitudinally reciprocatory bar 23 operatively positioned within the body 7 and extending outwardly of the upper end of the body. A handle 24 is fixed upon the upper end of the bar 23, and the latter is normally retained in uppermost position by means of a spring 25 confined between the handle and the end of the body 7, such normal position being determined by engage-

ment of the pin 20 with the upper ends of the slots 22.

The lower end of the bar 23 carries a plunger 26, positioned within the enlarged lower end of the tubular body 7, and adapted to engage a cap, delivered as previously described into the chamber 3, and force the cap into the mouth of a bottle positioned within the bell portion 2 of the body 1, the plunger 10 being actuated by resting the bell 2 upon the mouth end of a bottle and manually forcing down the handle 24. This action may be similarly accomplished in an automatic capping machine by fixedly supporting the bar 15 23 and elevating a bottle engaged with the bell 2, thus causing the body of the mechanism to slide upwardly on the bar 23 and effect the same relative movements of the parts herein described.

20 It has been the practice, in the mechanism hereinbefore described, to push the cap into the chamber 3 and permit it to drop to the lower end of that chamber where the cap is retained, by a slight constriction of the 25 chamber end, until forced through and into a bottle mouth by the plunger 26. Such arrangement will not operate successfully with certain types of caps having crimped edges, wherewith the constriction of the lower end 30 of the chamber 3 is not permissible, and which special types frequently lodge edge-wise in the chamber. To overcome this difficulty, I have provided novel means for receiving the cap when pushed into the chamber 35 3, and for lowering the cap in advance of the plunger 26 into position for proper seating in a bottle mouth.

My novel means to that end comprises a pair of laterally spaced fingers 27, each having a hook 28 normally positioned at opposite sides of the chamber 3 and immediately below the plane of the slot 15 through which the caps are pushed into the chamber 3, whereby a cap entering the chamber 3 passes 40 over the hooks 28 and rests thereupon. The fingers 27 are positioned in laterally opposite openings 29 provided in the side walls of the body parts 1 and 7, and are pivotally supported at their upper ends upon a yoke 45 30 which is freely mounted on the constricted lower portion of the bar 23 and extending laterally through the openings 29. The yoke 30 is retained normally in abutment with the plunger 26 by a coiled spring 31 50 confined between the yoke and a shoulder 32 in the bar 23. The fingers 27 are retained normally in inward position by springs 33 mounted on the yoke and bearing upon the outer faces of the respective fingers.

60 Each of the fingers 27 is provided on its inner face with a cam lug 34 adapted for engagement by the enlarged upper end 35 of the plunger 26, whereby the fingers are swung outward effecting the release of the cap resting on the hooks 28. Such engagement is

caused in the downward movement of the bar 23 and yoke 30 by abutment of the outer ends of the yoke with a pair of stop bars 36 secured to the body 7 across each of the openings 29 in such position that the descent of the cap carried by the hooks 28 is arrested just over the mouth of the bottle engaged with the bell 2, and the further descent of the bar 23 through the yoke 30, and against spring 31, carries down the plunger 26 until the enlarged portion 35 engages the cams 34, thereby spreading the fingers and releasing the cap. Upon continued descent of the bar 23, the plunger engages the cap, now resting upon the bottle, and forces it into the recess provided in the bottle mouth.

While the bar 23 is being forced downward, the arms 16 are operating to move the block 6 to rearward position in its slideway, thereby permitting another cap to drop into the path of the slide 13. Upon relieving the downward pressure upon the handle 24, the spring 25 lifts the bar 23 and restores the several operative parts to normal position, the slide 13 being moved forward and carrying the cap therebefore through the slot 15 and onto the hooks 28, in readiness for capping the next bottle.

I claim as my invention:

1. In a bottle capping mechanism, a reciprocatory plunger having an operative support, a member mounted on said support and normally movable with said plunger, a pair of elements movably supported on said member and disposed laterally of said plunger, said elements normally being positioned to retain a cap endwardly of said plunger, a stop for limiting the advance movement of said member, and means normally in the path of said plunger and engageable thereby to cause the movement of said elements to release said cap.

2. In a bottle capping mechanism, a reciprocatory plunger having an operative support, a member mounted on said support and normally movable with said plunger, a pair of elements swingably supported on said member and disposed laterally of said plunger, said elements being adapted in normal position to retain a cap endwardly of said plunger, a stop for limiting the movement of said member with said plunger, and a cam on each of said elements adapted for engagement by said plunger in the continued movement of said plunger, said engagement causing lateral movement of said elements effecting release of said cap.

In witness whereof I have hereunto attached my signature.
